Patented Dec. 4, 1917.

UNITED STATES PATENT OFFICE.

FREDERICK W. FULLERTON, OF ST. PAUL, MINNESOTA.

COUNTER.

1,249,060.

Specification of Letters Patent.

Patented Dec. 4, 1917.

Application filed March 24, 1915. Serial No. 16,613.

To all whom it may concern:

Be it known that I, FREDERICK W. FULLERTON, a citizen of the United States, residing at St. Paul, in the county of Ramsey and 5 State of Minnesota, have invented a new and useful Improvement in Counters, of which the following is a specification.

This invention relates to improvements in counters, and more particularly to that class 10 in which newspapers or other articles are arranged at the delivery end of a conveyer in marked groups, each group containing a predetermined number of papers being packed in convenient form for efficient han- 15 dling. My invention is applicable to that class of conveyers set forth in my companion application, Serial Number 628,598, filed May 20, 1911, although it can be employed in connection with other kinds of conveyers.

20 The primary objects of my invention are,

To deliver the papers in the delivery room of a printing establishment, such as a newspaper building, in smooth condition in the least possible time after the presses start.

25 To count the papers automatically in as-sorted groups of any predetermined number desired.

To prevent smutting and tearing of pa- 30 pers while they are being conveyed and counted.

To provide a device of its kind, which can be easily adapted for any kind of building construction.

35 The saving of labor and expense, and

35 The saving of waste and spoiled papers by eliminating carrier boys and unnecessary help around mechanical departments.

To these ends my invention comprises the 40 features of construction and combination of parts hereinafter more particularly de- scribed and claimed.

Figure 1 is a side elevation of a detail of a carrier system embodying my improvements; Fig. 2 is another side elevation of a 45 detail in which the parts are illustrated on a larger scale than in Fig. 1, and Fig. 3 is an end view of the construction illustrated in Fig. 1.

In the drawings, A and B indicate the 50 downward flights of pluralities of substantially parallel helical spring wire belts, each plurality being grouped in the manner set forth in my companion application above referred to. The belts constituting each 55 group are arranged with their sides 2 and 3 adjoining and spaced apart, said sides trav-

eling at substantially the same surface speed in a downward direction as indicated by the arrows in Fig. 1. The belts of each group are arranged parallel to each other and pass 60 around sheave pulleys 4 and 5 at their lower ends, the sheave pulleys 4 being mounted upon the shaft 6 at a lower level than the sheave pulleys 5 which are mounted upon the shaft 7. The shafts 6 and 7 are journaled in suitable frame work 8, said frame work being supported upon the stand 9 as illustrated or other suitable means. The belts constituting the flights A and B can be driven by any suitable means, the flight 70 A being positively driven by a chain belt 10 passing over a sprocket 11, which is mounted upon the shaft 6 while the method of driving the belts constituting the flight B not being illustrated, it being assumed 75 that they are driven from the upper end of the conveyer flight. Positioned below the delivery end of the coöperating flights A and B is a horizontal conveyer table C consisting of side bars 15 pivotally mounted 80 upon a shaft 16 at one end, said shaft being in turn journaled upon brackets such as 17 extending outwardly from the forward sides of the stand 9. Journaled upon the outer ends of the side bars 15 is a shaft 18, which 85 carries a plurality of sheave pulleys 19 suitably spaced apart and in alinement with a plurality of sheave pulleys 20, which are secured upon the shaft 16. Passing around the peripheries of these pulleys 19 and 20 90 are a plurality of suitably coiled spring wire belts 21, the upper sides of which lie in substantially a horizontal plane, and form a table surface upon which the papers D in folded condition are packed and counted. 95 A succession of papers in overlapping condition are carried downwardly by the conveyer between the sides 2 and 3 of the downward flights, and are transferred in a steady procession on to the conveyer table. 100 The turn of this procession of papers from a downward to a substantially horizontal direction is made by a downwardly slanting auxiliary conveyer E, consisting of a plurality of sheave pulleys 22 mounted and 105 driven by the shaft 6 and a plurality of pulleys 23 mounted upon a shaft 24, all of said pulleys being suitably spaced apart and arranged to receive parallel flexible spring wire belts 25 around their peripheries. The 110 shaft 24 is journaled in an arm 26 of the frame 8 and the upper sides 27 of the belts

25 slant downwardly and outwardly from the lower delivery end of the flights A and B toward the upper sides 21 of the belts on the table C. The auxiliary flight of belts 5 25 moving forwardly in the direction of the arrows illustrated in Fig. 1 deflect the procession of papers from a direct downwardly into a slanting direction. The shaft 6 carries an eccentric 28, which reciprocates a 10 ratchet arm 29, the lower end of said arm engaging the teeth of a ratchet wheel 30 mounted upon the shaft 16, so that during every revolution of the shaft 6, the ratchet wheel 30 is stepped forward and the shaft 15 turned, thereby moving the upper sides 21 of the belts on the conveyer table in the direction of the arrows indicated in Fig. 1. As a result the conveyer belts forming part 20 of the delivery table are moved forwardly at a slower surface speed than that of the conveyer belts constituting the downward flights and the auxiliary flight. This slower rate of speed of the carrier belts on the delivery table causes the papers to be closely packed in reclining position, convenient to 25 be lifted by the operator from the table in assorted groups, and enabling the carrier table to move substantially continuously in a forward direction.

30 Located immediately above the upper sides 27 of the auxiliary belts are a plurality of idle wheels 35 mounted upon the shaft 36, said shaft in turn being mounted in guide grooves 37 on downwardly and inwardly slanting arms 38 constituting part of said frame. The peripheries of these idle wheels 35 bear down and roll over the surfaces of the papers, as they are being carried downwardly by the upper sides 27 of the auxiliary flights of belts, thus holding the papers down and assisting in causing them to move forward in regular order to be packed on the delivery table. Immediately below the idle wheels 35, which act as guides in the 45 manner stated is my improved counter, consisting as follows:

Mounted upon the guide 54 to be herein-after described is an impaling element 40 in the form of a bell crank lever pivoted by the 50 pin or bolt 41 upon said arm and provided at the outer end of one of its arms with a point 42 and in the outer end of its adjacent member with a toothed segment 43. The teeth of the toothed segment mesh with the 55 teeth of a sector gear wheel 44 which is journaled on the shaft 24 and carries an operating lever 45 extending at an incline downwardly. The lower end of the operating lever 45 has journaled thereon an anti-friction roller 46, which bears downwardly 60 upon the periphery of a flange 47 on one of the sheave pulleys 20. The flange 47 has a depression 48 formed in its periphery into which the roller 46 passes during each revolution of the shaft 16. An arm 49 extend-

ing downwardly from the guide 54, to be herein-after described, has attached to it a helical tension spring 50, one end of which is attached to the lever 45, thus causing the antifriction roller 46 to follow the periphery of the flange 47 as the pulley 20 having said flange revolves. During every revolution of the pulley having said flange the impaling element is caused to swing upwardly and the point of this impaling element being positioned between the carrier wheels 23, so as to engage a rear corner of one of the papers which is being carried by the conveyer, thus holding that paper and causing it to swing cornerwise leaving one of its forward corners extending from the procession of papers conducted by the conveyer and making off at regular intervals in synchronism with the movement of the conveyer and the press from which the papers are being delivered by the conveyer, predetermined groups or numbers of papers. Every paper which is offset from the procession of overlapping papers in this manner projects from the pack D which is formed on the table, making it easy for the operator to select the groups of papers which have been counted and remove them from the table. The number of papers counted can be determined by the number of depressions such as 48 and the intervals between them in the periphery of the flange 47. The guide wheels 35 hold the papers down within operative reach of the point, and an auxiliary spring guide arm 52 mounted upon the shaft 36 and pressed downwardly upon the papers also assists in retarding and evening the papers in position on the table. The outer end of the table is supported by a stand 53 upon which the shaft 18 is journaled, and it will be observed that the entire table can be lifted with the stand 53 and tilted upwardly about the shaft 16 as a center when desired. A guide or stripper 54 in the form of a segment of a broad faced pulley mounted rigidly upon the stationary shaft 24, strips the papers from the point and is formed with an opening 55 through which the point 42 of the impaling element 40 moves upwardly and downwardly. On the side of the guide 54 the pivot support 45 for the impaling element is secured.

The counting and packing mechanism set forth admits of application to various conveyer structures and while the apparatus shown illustrates one mode of application of the invention the novel features can be modified and applied in use in various ways within the spirit of the invention.

In accordance with the patent statutes, I have described the principles of operation of my invention, together with the apparatus which I now consider to represent the best embodiment thereof, but I desire to have it understood that the construction

shown is only illustrative, and that the invention can be carried out by other means and applied to uses other than those above set forth within the scope of the following 5 claims.

Having described my invention, what I claim as new and desire to protect by Letters Patent is:—

1. In combination with a carrier for feeding a procession of papers in evenly overlapping condition, means for movably holding certain members of said procession after said procession has been formed while the papers arrested are turned by the forward 10 movement of said procession until portions of the arrested papers project from said procession.
2. In combination with a carrier for feeding a procession of papers in evenly overlapping condition, a spur forming a pivot point about which a paper is turned by the forward movement of said procession, and means for periodically thrusting said spur 15 against certain papers of said procession and holding said papers impaled thereon while said papers are turned by the forward movement of said procession until portions thereof project from said procession.
3. In combination with a carrier for feeding a procession of papers in overlapping 20

condition, a spur associated with said carrier, means for thrusting said spur against and holding certain of said papers of said procession impaled thereon while the forward movement of said procession turns said impaled papers until portions thereof project from said procession and a conveyer table upon which said papers of said procession are collected. 35

4. In combination with a carrier for feeding a procession of papers in evenly overlapping condition, a spur associated with said carrier, means for periodically thrusting said spur against certain of said papers 40 of said procession and impaling said papers thereon while they are turned by the forward movement of said procession until portions thereof project from said procession, a conveyer table upon which said papers are collected and means for stepping said table to advance said papers in stacked condition from and in synchronism with the forward movement of said carrier. 50

In testimony whereof, I have signed my name to this specification, in the presence 55 of two subscribing witnesses.

FREDERICK W. FULLERTON.
